UNITED STATES PATENT OFFICE.

SAMUEL SEGAL, OF NEW YORK, N. Y., ASSIGNOR TO SEGAL METAL PRODUCTS COMPANY, INC., OF NEW YORK, N. Y., A CORPORATION OF DELAWARE.

CYLINDER-LOCK.

1,399,159.

Specification of Letters Patent.

Patented Dec. 6, 1921.

Application filed December 10, 1920. Serial No. 429,627.

To all whom it may concern:

Be it known that I, SAMUEL SEGAL, a citizen of the United States, and a resident of New York, in the county of New York and State of New York, have invented certain new and useful Improvements in Cylinder-Locks, of which the following is a specification.

My invention relates to cylinder or pin 10 tumbler locks, the invention relating more particularly to the manner in which the cylinder itself is held or secured to the door to which the lock is applied.

In the conventional or ordinary form of 15 cylinder locks the cylinder proper holding the pin tumblers and key plug is at present usually held or secured within an annular opening in the door by means of suitable bolts extending through a plate supported 20 in or on the door or through a wall of the lock casing itself and engaging the cylinder or a portion thereof to prevent said cylinder from being withdrawn forwardly through the annular opening and thus preventing access 25 to the lock mechanism from without the door. This means of fastening the cylinder in position is cumbersome and impracticable as the length of the fastening bolts varies depending on the thickness of the 30 door as is obvious. If the bolts supplied are short and a thick door is encountered new bolts of the correct length must be secured while if long bolts are supplied and a thin door is encountered the bolts must be 35 cut off, this requiring measuring of the thickness of door and length of bolts, the locksmith's time and the proper tools to properly perform the cutting operation. Moreover, if the bolts are too long, the average 40 layman when attempting to himself apply the lock to the doors must have the bolts cut to the required length which entails additional expense or, if he attempts to cut them himself, he is very apt to injure the bolts or bend them thus rendering them un- 45 serviceable.

It is the principal object of my invention to obviate the disadvantages hereinbefore recited and to provide novel and efficient 50 means whereby the lock cylinder may be properly secured or fastened in position without the provision of means which must be fastened to the lock casing or to a separate plate.

A further object of my invention is the 55 provision of suitable and novel means adapted to secure the lock cylinder in position in an opening in the door irrespective of the thickness of said door, which means shall also act to draw the cylinder within 60 said opening whereby the conventional escutcheon carried by or forming a part of said cylinder will be clamped against the door.

A further object of the invention is the 65 provision of a lock cylinder which may be secured in proper position by novel and effective means, said lock cylinder being entirely free from and disconnected from the lock casing or parts thereof. 70

A further object of the invention is the provision of novel means adapted to engage the lock cylinder and the wall of the opening in which the cylinder is mounted which shall prevent the forward withdrawal of said 75 cylinder through said opening.

Still a further object of the invention is the production of a novel spindle connected to the key plug within the cylinder and which is adapted to operate the lock mechanism, which spindle shall be adjustable as to its length to meet varying conditions as respects the thickness of the door. 80

Further and other objects and advantages of the invention will appear from the following description, the invention consisting in the novel parts and combinations of parts hereinafter more particularly described and then specified in the claims. 85

In the accompanying drawings: 90

Figure 1 is a horizontal section through a door showing my invention in elevation applied thereto.

Fig. 2 is a side elevation of the invention as applied to a door which is shown in section. 95

Fig. 3 is an end view of the lock cylinder.

Fig. 4 is a horizontal section on the line 4-4 of Fig. 1.

Fig. 5 is a front elevation of a modification. 100

Fig. 6 is an end view of said modification.

Fig. 7 is a front elevation of a further modification.

Fig. 8 is an end view of said modification. 105

Referring in detail to the drawings:

1 indicates a door provided with an annular opening 2 extending therethrough. 3

indicates the cylinder of an ordinary pin tumbler lock supporting pin tumblers (not shown) in the tumbler housing 4 thereof, said cylinder holding therein the conventional key plug (not shown). The key plug has fastened thereto as by screws 5 a slotted end plate 6 engaging the end of the cylinder 3 to prevent forward withdrawal of said plug through said cylinder. 7 indicates 5 a spindle secured to the plug and extending rearwardly through the slot in the end plate 6 and through the opening 2. Said spindle is provided with a series of depressions 8 therein adapted for engagement by 10 a series of corresponding buttons 9 on a sleeve 10 fitting over the spindle 7 and slideable thereon. The end of the spindle 7 or of the sleeve 10 is adapted to engage the lock mechanism, as ordinarily, to actuate the 15 same when a key is inserted in the plug in the cylinder 3 to turn said plug and said spindle. The lock casing or mechanism are not shown but they may be of any suitable type. The construction of spindle shown 20 permits its length to be varied, as is obvious, depending on the thickness of the door to which the lock is applied and the frictional engagement of the buttons 9 with the depressions 8 will hold the sleeve 10 in any 25 desired adjusted position.

The cylinder 3 is provided with the usual annular face plate 11 of a size permitting it to fit snugly within the opening 2, said plate being preferably integral with said 30 cylinder 3 and the tumbler housing 4, thereof, these parts preferably all comprising a single structure. The face plate is provided with the usual annular opening (not shown) receiving the key plug within the cylinder 3. 12 indicates a ring or escutcheon which 35 may be integral with the said face plate 11 and which is adapted to engage the face of the door adjacent the opening 2. 13 indicates ears which are preferably integral with 40 said cylinder 3 and which are provided with interiorly screw-threaded perforations receiving the screws 14.

15 indicates cylinder fasteners each having a groove 16 in the body thereof, a pointed prong or spur 17 at the inner end thereof and a flat shoulder 18 adjacent said prong or spur. The opposite ends of said cylinder fasteners are reduced as at 19, said reduced ends being provided with transverse pins 20 forming a part thereof. 21 indicates fingers on the inner side of the face plate 11 and preferably integral therewith and receiving therebetween the reduced ends 19 of the cylinder fasteners 15, said fingers being bent or turned over the transverse pins 20 whereby a pivoted connection is provided between the cylinder fasteners and the cylinder or its face plate.

To properly position the cylinder within

the opening 2 the screws 14 are unscrewed or 65 unthreaded and brought into extreme inner position within the perforated ears 13 and the cylinder fasteners are swung inwardly on their pivots into a position whereby their adjacent sides or backs are substantially parallel. The cylinder is then inserted in the opening 2 and the escutcheon 12 held against the face of the door. The screws then are threaded or screwed forwardly through the 70 perforated ears 13, the ends thereof engaging the grooves 16 in the cylinder fasteners thereby forcing said fasteners to swing or spread outwardly, whereby the prongs or spurs 17 thereof will bite into the wall of the opening 2 and the flat shoulders 18 will preferably engage said wall. This, as is obvious, securely locks the cylinder in the proper position within the opening 2 and prevents rotation of the cylinder or withdrawal of the same through said opening 75 until the screws 14 are unscrewed and the prongs or spurs 17 released from their biting engagement with the wall of said opening. The forcing of the prongs or spurs 17 into the wall of the opening 2 by means of 80 the screws 14 in the manner described not only acts to effectively and firmly fasten the cylinder in proper position within said opening but obviously, simultaneously acts to draw the cylinder bodily within said opening 85 whereby the escutcheon 12 is firmly clamped against the face of the door both in the preferred form of the invention and in the modifications hereinafter described.

Broadly the invention includes either the 90 pivoting or engagement of the cylinder fasteners to or with the cylinder *per se*, its face plate 11, tumbler housing 4 or ears 13 or other parts of said cylinder and the supporting of the screws 14 by said cylinder or 95 any of said parts and with this explanation the term "cylinder" when used in conjunction with said cylinder fasteners or said screws is to be construed broadly in the appended claims as including the cylinder 100 *per se* or any or all of its parts unless said parts are claimed specifically.

In the modification shown in Figs. 5 and 6 13^a indicates perforated ears which are 105 preferably integral with the cylinder 3 and which are turned or inclined from the horizontal as illustrated. Said ears 13^a are provided with screw-threaded perforations, as in the preferred form of the invention, receiving the screws 14^a which are threaded 110 therethrough. The ends of said screws 14^a are adapted to bite directly into the wall of the opening 2 instead of bearing against an additional part, as for instance the cylinder fasteners 15 in the preferred form, and forcing said additional part to bite into said 115 opening wall. While the invention of the modification may be used in conjunction 120

with doors of varying thicknesses, still there is a limit to the thickness of the door on which it may be used as, if the door is extremely thick, access may not be had to the heads of the screws 14^a by a screw-driver inserted within the rear of the opening 2 due to the inclined position of said screws. This difficulty, however, is obviated in the preferred form of the invention in which 10 the position of the screws is at right-angles to the plane of the door.

In the modification illustrated in Figs. 7 and 8 the invention of the preferred form is embodied in the device. The modification 15 merely differs from the preferred form in that the cylinder 3 is centrally located as respects the face plate 11. This permits the employment of three perforated ears 13, three screws 14 and three cylinder fasteners 20 15 with accompanying parts for said elements having the position shown in the figures, instead of two of each of said parts as in the preferred form, whereby a more secure and effective locking of the cylinder in 25 the proper position may be effected as is manifest.

What I claim as my invention is:

1. In a lock, the combination with a wall 30 having an opening therein, of a cylinder associated with said wall and means engaging said cylinder and the wall of said opening to lock the cylinder in position and to draw said cylinder within said opening.

2. In a lock, the combination with a wall 35 having an opening therein, of a cylinder within said opening and means engaging said cylinder and adapted to bite into the wall of said opening to lock the cylinder against withdrawal, and to draw said cylinder within said opening.

3. In a lock, the combination with a wall having an opening therein, of a cylinder 40 within said opening and means carried by said cylinder and adapted to bite into the wall of said opening to lock the cylinder against withdrawal and to draw said cylinder within said opening.

4. In a lock, the combination with a wall 45 having an opening therein, of a cylinder within said opening and means engaging said cylinder and provided with a prong adapted to bite into the wall of said opening to lock the cylinder against withdrawal and to draw said cylinder within said opening.

5. In a lock, the combination with a wall having an opening therein, of a cylinder 50 within said opening and means pivoted to said cylinder and provided with a prong adapted to bite into the wall of said opening to lock the cylinder against withdrawal and to draw said cylinder within said opening.

6. In a lock, the combination with a wall

having an opening therein, of a cylinder 65 within said opening, a key plug within said cylinder, a spindle fastened to said key plug and extending rearwardly through said opening and a sleeve carried by said spindle and slidably thereon.

7. In a lock, the combination with a wall 70 having an opening therein, of a cylinder within said opening, a key plug within said cylinder, a spindle fastened to said key plug and extending rearwardly through said opening and provided with a depression therein and a sleeve carried by said spindle and provided with a button adapted to frictionally engage said depression.

8. In a lock, the combination with a wall 80 having an opening therein, of a cylinder within said opening, fastening means engaging said cylinder and means carried by said cylinder adapted to force said fastening means to bite into the wall of said opening.

9. In a lock, the combination with a wall 85 having an opening therein, of a cylinder within said opening, fastening means engaging said cylinder, an ear on said cylinder and means carried by said ear adapted to force said fastening means to bite into the wall of said opening.

10. In a lock, the combination with a wall 90 having an opening therein, of a cylinder within said opening, a cylinder fastener engaging said cylinder and provided with a prong thereon and means within said opening adapted to engage said cylinder fastener and force the prong thereof to bite into the wall of said opening.

11. In a lock, the combination with a wall 95 having an opening therein, of a cylinder within said opening, a cylinder fastener pivoted to said cylinder and provided with a prong thereon and means carried by said cylinder adapted to engage said cylinder fastener and force the prong thereof to bite into the wall of said opening.

12. In a lock, the combination with a wall 100 having an opening therein, of a cylinder within said opening, a cylinder fastener pivoted to said cylinder and provided with a prong thereon, an ear on said cylinder and a screw threading through said ear and adapted to engage said cylinder fastener and force the prong thereof in the wall of said opening.

13. In a lock, the combination with a wall 105 having an opening therein, of a cylinder within said opening, an escutcheon on said cylinder and means engaging said cylinder and adapted to bite into the wall of said opening to lock the cylinder against withdrawal and to clamp said escutcheon against said wall.

14. In a lock, the combination with a wall 110 having an opening therein, of a cylinder within said opening, an escutcheon carried

by said cylinder and means carried by said cylinder and provided with a prong adapted to bite into the wall of said opening to lock the cylinder against withdrawal and to force 5 said escutcheon to engage said wall.

15. In a lock, the combination with a wall having an opening therein, of a cylinder within said opening and means within said opening and engaging said cylinder and 10 adapted to be spread outwardly to bite into the wall of said opening and lock said cylinder against withdrawal.

16. In a lock, the combination with a wall having an opening therein, of a cylinder 15 within said opening, a cylinder fastener engaging said cylinder and provided with a prong thereon and a groove therein and means carried by said cylinder adapted to enter said groove and force said prong to 20 bite into the wall of said opening.

17. In a lock, the combination with a wall having an opening therein, of a cylinder within said opening, a cylinder fastener engaging said cylinder and provided with a 25 prong and a shoulder thereon and means carried by said cylinder adapted to engage said cylinder fastener to force the prong thereof to bite into the wall of said opening

and the shoulder to engage the wall of said opening.

18. In a lock fastening, the combination with a wall having an opening therein and the lock cylinder within said opening, of a flange associated with said cylinder and adapted to engage the surface of the wall 35 and an adjustable device mounted on said cylinder and adapted to engage the wall of the opening to draw said flange against the surface of the wall.

19. In a lock fastening, the combination 40 with a wall having an opening therein and the lock cylinder within said opening, of a flange associated with said cylinder and adapted to engage the surface of the wall and a pair of spreading arms attached to the 45 cylinder and adapted to engage the wall of the opening and, upon actuation, to draw said flange against the surface of the wall.

Signed at New York, in the county of New York and State of New York, this 9th day 50 of December, A. D. 1920.

SAMUEL SEGAL.
